UNITED STATES PATENT OFFICE.

DENNIS I. HARTMANN, OF NEW YORK, N. Y.

SHAVING AND LATHER BRUSH.

1,092,710.

Specification of Letters Patent.

Patented Apr. 7, 1914.

Application filed May 7, 1913. Serial No. 766,240½.

To all whom it may concern:

Be it known that I, DENNIS I. HARTMANN, a citizen of the United States, and a resident of the city of New York, borough of Brooklyn, in the county of Kings and State of New York, have invented a new and Improved Shaving and Lather Brush, of which the following is a full, clear, and exact description.

- 10 This invention relates to toilet devices and has particular reference to combined massager and lather or shaving brush, the same including a handle, a set of bristles and a massager carried by the handle and located 15 within the mass of bristles, the arrangement being such that the bristles may be employed as usual for the application of soap to the beard and then for the massager to be brought into use by a slightly greater pressure 20 upon the handle for the purpose of forming the lather directly upon the face and without requiring the operation of the fingers.

The foregoing and other objects of the invention will hereinafter be more fully described and claimed and illustrated in the drawings forming a part of this specification in which like characters of reference indicate corresponding parts in both the 30 views, and in which—

Figure 1 is a vertical sectional view of a preferred embodiment of the invention; and Fig. 2 is a transverse section of the same on the line 2—2 of Fig. 1.

35 The several parts of the device may be made of any suitable materials, and the relative sizes and proportions, as well as the general design of the mechanism, may be varied to a considerable extent without deviating from the spirit of the invention 40 hereinafter more fully set forth and specifically claimed.

A device made in accordance with this invention includes a ferrule or thimble 10 having open upper and lower ends which are slightly smaller in diameter than the middle portion of the thimble. The upper end is threaded internally at 11, and the lower end has a tapered smooth interior surface 12. 45

50 A body of bristles 13 is provided in its in-

terior, preferably at the center, with a massager comprising a stem 14 and a body or head 15 having a series or set of downwardly projecting fingers 16. Said head and fingers are preferably arranged well 55 within the bristles so that the brush may be used for the application of soap and water without bringing the massager into operation. By applying pressure, however, to the handle the bristles will flatten out so 60 as to permit the head and fingers to be brought into use for the purpose of forming the lather and softening the beard. The upper ends 17 of the bristles surround the upper end 14' of the stem, and having been 65 impregnated with any suitable cement 18', form a mass or clump of material which is inserted into the smooth tapered end 12 of the thimble to any desired extent. After this has been done, more cement is poured 70 into the upper end of the thimble covering the ends of the bristles and stem in a substantial manner and to any desired depth. Subsequently, the handle 18 having a threaded hub 19 is screwed snugly into the 75 threaded end of the thimble making a solid and strong closure for the device.

Having thus described my invention, I claim as new and desire to secure by Letters Patent:—

80 The herein described brush comprising a thimble having an internal thread at one end and a smooth internally tapered surface at the other end, the middle portion of the thimble being larger in diameter than said 85 ends, a mass of bristles, a massager carried within the mass of bristles and including a stem extending with the bristles into said thimble at one end and having at its other end a head with a series of projecting fingers, a handle having threaded engagement in the threaded end of the thimble, and binding material filling the mass of bristles within the thimble and surrounding the upper end of said stem, substantially as and 90 for the purposes set forth.

DENNIS I. HARTMANN.

Signed in presence of—

CHARLES R. FAY,

WILLIS BOUGHTON.
